PRESSURE FLUID MOTOR

Filed Sept. 30, 1929

UNITED STATES PATENT OFFICE

ELMER G. GARTIN, OF CLAREMONT, NEW HAMPSHIRE, ASSIGNOR TO SULLIVAN
MACHINERY COMPANY, A CORPORATION OF MASSACHUSETTS

PRESSURE FLUID MOTOR

Application filed September 30, 1929. Serial No. 396,337.

This invention relates to pressure fluid motors and more particularly to improved pressure fluid motors of the impact type.

An object of this invention is to provide an improved pressure fluid motor. Another object is to provide an improved pressure fluid motor of the valveless type. A further object is to provide an improved pressure fluid motor of the impact type having improved fluid distribution means. Still another object is to provide an improved valveless motor of the hammer piston type whereby with the improvements incorporated therein it is made possible to form the motor cylinder with a substantially uniform bore and the hammer piston with a substantially smooth exterior surface, thereby eliminating all differential cylinder bores, differential piston heads or spools and external circumferential grooves on the piston. A still further object is to provide an improved valveless type hammer motor in which extreme simplicity and ruggedness of design are attained without sacrifice of efficiency or power. These and other objects and advantages of this invention will, however, hereinafter more fully appear.

In the accompanying drawings there is shown for purposes of illustration one form which the invention may assume in practice.

In the drawings,—

Fig. 1 is a central longitudinal sectional view illustrating a percussive tool having the illustrative embodiment of the improved pressure fluid motor incorporated therein.

Fig. 2 is a view similar to Fig. 1 showing the hammer piston in a different position.

Fig. 3 is a transverse sectional view taken substantially on line 3—3 of Fig. 1.

In this illustrative construction there is shown a percussive tool of the pressure fluid operated type including a motor cylinder 1 having a bore 2 in which there is mounted for reciprocatory movement a hammer piston 3. This hammer piston is of uniform diameter fitting the bore 2 and has formed thereon a forwardly projecting striking bar 4 which, when the hammer piston nears the forward end of its forward stroke, enters a reduced bore 5 formed within the integral

front head of the motor cylinder. In the present construction, carried within a bore 6 within the front end of the motor cylinder is a chuck bushing 7 which supports the shank of a working implement 8, this shank having 55 reciprocating movement within the chuck bushing and its rear end extending into a position to receive the impacts imparted thereto by the striking bar of the hammer piston. The implement 8 has formed thereon a usual collar 9 arranged within a chamber 10 formed within a retaining member having a central opening 12 through which the shank of the implement 8 extends. Interposed between the retaining member 11 60 and a split retaining washer 13 is an annular shock absorbing member 14. The elements 11, 13 and 14 of the chuck are supported within a chuck housing 15 secured as by a transverse bolt 16 to the forward end of the motor 70 cylinder. The rear end of the cylinder bore of the motor is closed by a detachable back head member 17 which is held in position by a handle member 18 suitably secured to the motor cylinder. Formed within this 75 handle member is a fluid supply passage 19 through which pressure fluid is conducted under the control of a throttle valve 20 to supply passages 21 which communicate with an annular groove 22 herein preferably 80 formed in the cylinder wall midway between the ends of the cylinder bore 2. As shown, one side of the hammer piston 3 is flattened at 23 throughout a substantial portion of its length, and formed centrally within the 85 hammer piston is a chamber 24. Herein formed integral with the head member 17 is a hollow sleeve-like extension 25 projecting forward within the piston chamber 24, the forward end of this extension being closed 90 by a transverse wall 26. The diametrically opposite sides of the extension 25 are flattened at 27 and the walls of this extension are traversed by lateral ports 28. The interior of the extension 25 communicates with the atmosphere through a lateral passage 29 formed in the back head 17. The cylinder bore 2 is internally enlarged or grooved at 30 and 31 at its front and rear ends respectively to provide fluid conducting passages 95 100

or grooves. A passage 32 connects the bore 5 directly to atmosphere.

The operation of the improved pressure fluid motor will now be described. When 5 the parts are in the position shown in Fig. 1 with the throttle valve 20 opened, pressure fluid flows through the supply connection 19 past the throttle valve 20 and through passages 21 to the annular groove 22 formed 10 centrally in the wall of the motor cylinder. At this time the front end of the cylinder bore is connected directly to exhaust through bore 5 and passage 32. The pressure fluid flows from the central groove 22 past the flattened 15 portion 23 on the piston 3 to the enlarged rear grooved or enlarged portion 31 of the cylinder bore. The pressure fluid acts on the annular pressure area at the extreme rear end of the piston, causing the latter to 20 move forward, at the same time admitting pressure fluid through the flattened portions 27 on the extension 25 to the piston chamber 24. The pressure acting on the pressure area 25 at the forward end of the piston chamber 24 supplements the pressure acting on the annular rear end surface of the piston, thereby driving the piston forward within the cylinder bore to deliver a powerful blow on the shank of the implement 8. As the piston 30 moves forward the flattened portion 23 on the piston moves out of communication with the internally enlarged rear end portion 31 of the cylinder bore, thereby cutting off the flow of pressure fluid to the rear end of the 35 cylinder bore. The pressure fluid at the rear end of the cylinder bore then acts expansively, driving the piston forward. As the hammer piston 3 moves further forward the ports 28 formed in the extension 25 are 40 opened, thereby connecting the cylinder bore at the rear end of the hammer piston directly to atmosphere through the passage 29. As the piston continues its forward movement the flattened portion 23 on the piston moves 45 into communication with the internally enlarged front end 30 of the cylinder bore, connecting the front end of the cylinder bore with the fluid supply groove 22. As the hammer piston nears the forward end of its 50 working stroke the striking bar 4 enters the bore 5, thereby closing the passage 32 and cutting off communication of the front end of the cylinder bore with the exhaust. Upon continued forward movement of the hammer 55 piston the striking bar 4 delivers its blow on the shank of the implement 8. When the parts are in the position shown in Fig. 2 pressure fluid flows through passages 21, annular groove 22, flattened portion 23 on the 60 piston and groove 30 to the forward end of the cylinder bore to act on the front pressure area on the hammer piston, driving the latter rearward. As the hammer piston moves rearward the flattened portion 23 on the piston 65 is moved out of communication with the

front end of the cylinder bore and the pressure within the front end of the cylinder bore then acts expansively, driving the piston rearward. Upon continued rearward movement of the piston the ports 28 are first closed, 70 cutting off the exhaust for the rear end of the cylinder bore and upon further movement of the piston the striking bar 4 moves out of the bore 5, opening the front end of the cylinder bore directly to exhaust through passage 32. At substantially the same time the rear end of the cylinder bore is brought into communication with the supply groove 22 by the flattened portion 23 on the piston, the piston moving rearward by momentum to 75 complete its return stroke. The cycle of operation described above is then repeated, thereby causing the hammer piston to reciprocate rapidly within the motor cylinder, thereby causing a hammering action to be 80 imparted to the shank of the implement 8.

As a result of this invention an improved pressure fluid motor is provided which is extremely powerful and efficient and at the same time is simple and rugged in design. 90 It will further be noted that an improved valveless pressure fluid motor is provided wherein by the improvements disclosed herein it is possible to form the cylinder bore of a substantially uniform diameter and the hammer piston with a substantially smooth exterior surface, thereby eliminating all differential cylinder bores, piston heads or spools, and circumferentially extending 95 grooves on the piston. It will still further be evident that by providing a valveless motor having the improved motor exhaust arrangement and a cylinder with a substantially uniform bore and a hammer piston of substantially uniform diameter, the cost of manufacture has been materially reduced and a 100 more rugged and efficient motor produced.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, a cylinder, a piston reciprocable therein and having a bore closed save at its rearward end, piston controlled means for admitting fluid to said cylinder to effect opposite movements of the piston in alternation, and means for exhausting fluid from the cylinder including a tube having a portion providing a lateral surface conforming in shape to and having a working fit with the wall of the bore in the piston and provided with a port opening through said portion within the borders of said surface.

2. In a pressure fluid motor, a cylinder, a piston reciprocable therein and having a bore closed save at its rear end, piston controlled means for admitting fluid alternately to opposite ends of said cylinder, means for exhausting fluid from the cylinder including a tube extending into the bore in the piston and having the communication of its own bore with the end of the cylinder in which it lies controlled by said piston, and means for effecting constant communication between the inner end of said piston bore and the last mentioned end of said cylinder.
3. In a pressure fluid motor, a cylinder, a piston reciprocable therein and having a longitudinal bore closed save at one end and means for effecting reciprocation of said piston including means for intermittently supplying fluid under pressure to act upon the end of the piston through which said bore opens, means telescoping within said bore controlling exhaust of the fluid so admitted, and means for connecting the innermost end of the bore constantly in communication with the space within the cylinder bore adjacent said end of the piston.
4. In a pressure fluid motor, a cylinder, a piston reciprocable therein and having a longitudinal bore closed save at one end and means for effecting reciprocation of said piston including piston controlled means for intermittently supplying fluid under pressure to act upon the end of the piston through which said bore opens, means telescoping within said bore controlling exhaust of the fluid so admitted, and means for connecting the innermost end of the bore constantly in communication with the space within the cylinder bore adjacent said end of the piston.
5. In a pressure fluid motor, a cylinder, a piston therein having a bore closed at one end, said cylinder having an inwardly projecting member telescoping with said bore, means for imparting opposite movements to said piston including means for admitting pressure intermittently to act on the inner end of said bore and on the end of the piston surrounding the mouth of the bore, and exhaust means controlled by piston movement and including a passage formed in said projecting member.

In testimony whereof I affix my signature.
ELMER G. GARTIN.
